UNITED STATES PATENT OFFICE

WILHELM REINERS AND GUSTAV KAHLISCH, OF MUNICH-GLADBACH, GERMANY, AS-
SIGNORS TO W. SCHLAFHORST & CO., OF MUNICH-GLADBACH, GERMANY, A CORPO-
RATION OF GERMANY

BREAKAGE-INDICATING MECHANISM FOR WARPING MACHINES AND THE LIKE

Application filed March 8, 1929, Serial No. 345,345, and in Germany March 13, 1928.

The invention relates to mechanisms indicating breakage of a thread and intended for warping frames and the like and the creels co-operating therewith.

The mechanisms hitherto known for automatically indicating breakage of a thread are designed to give upon a thread breaking either light or color signals by purely electric means or other signals by mechanical or electro-mechanical means. In all these mechanisms an individual signal is provided for each thread. Recently these mechanisms however have been abandoned, as, on the one hand, owing to the comparatively great number of threads treated in these machines and to the small space existing between them, the space at disposal for each individual thread signal is too small to enable the provision of a sufficiently plainly perceptible signal, and as, on the other hand, the first and maintenance costs of these mechanisms are too high.

The invention has for its object to obviate these draw-backs, which object is obtained by not providing a signal for each thread, but a common signal only for groups or ribbons of threads. Upon thus a thread or several threads breaking in the respective group or ribbon, the appurtenant common signal will at once indicate the group or ribbon in which the breakage occurred, and this by a signalling means of so great and easily perceptible dimensions that the place on the machine or creel where the breakage took place can be found quickly and absolutely reliably.

As according to the present invention all the stop motion feelers of a group or ribbon of threads have common contact plates, besides the expensive individual signal also the electric conduit leading to these individual signals is dispensed with, this resulting in the considerable reduction aimed at of the costs of the entire mechanism. The signals themselves may be given optically, e. g. by electric lamps or colored plates, or at the same time acoustically by electrically or mechanically actuated bells or the like and may be tripped purely electrically or electro-mechanically or mechanically. The signals

may be provided in close proximity of the stop motion feeler mechanism, e. g. on the feeler bars of the creel, as in the embodiments illustrated, or on any other place of the creel, above it or on the warping machine 55 itself without deviating from the scope of the invention.

In order that the invention can be more easily understood, several embodiments of the same are illustrated in the accompanying 60 drawings, in which

Figure 1 is a sectional side view of the first embodiment,

Figure 2 is a similar view with some parts in other position,

Figure 3 is a front view of the creel of a warping machine of known design and equipped with the new indicating mechanism,

Figure 4 is a view similar to Figure 1 of 70 another embodiment,

Figure 5 is a similar view with some parts in other position,

Figure 6 illustrates a board on which the electric or color signals or electro-magnetic 75 drop plate signals can be applied together.

Figure 7 illustrates in a view similar to Figure 1 a third embodiment, and

Figure 8 is a similar view with some parts in other position.

As is to be seen from Figure 3, in place of the usual thread guiding bars which guide the threads in the form of a ribbon from the bobbin to the warping machine, bar-shaped carriers 1 to 9 are provided on each side of 85 the creel, which carriers have mounted on them, instead of the usual eyelets for the threads, double-armed feelers or guide hooks 10, known in themselves, the number of these feelers corresponding to the maximum number of threads of the individual group. As is to be seen from Figures 1 and 2, the feelers 10 are able to swing about a common shaft 11. 12 denotes an electrically conductive plate provided on each bar, which plates are 95 conductively connected to a conductor 13 common to all plates. The conductor 13 in turn is electrically connected to the electro-magnetic stop mechanism of the warping machine. Upon a thread breaking, the re- 100

spective feeler 10, owing to the greater weight of its longer arm, lowers into the position illustrated in Figure 2 whereby the circuit is closed and the machine automatically stopped. In place of the double-armed stop feelers 10, of course any other suitable feelers or stop members may be made use of.

In the embodiment illustrated in Figures 1 and 2, an electric signal, e. g. an incandescent lamp 14, is provided for each of the thread guiding bars 1 to 9. The lamp 14 is conductively connected both with the appurtenant contact plate 12 and with the metal rod or pipe 15 of the frame to which 15 rod the other conduit is electrically connected. Upon thus a thread of a group or ribbon breaking and the feeler 10 falling down to position of Figure 2, the circuit is closed whereby not only the above-mentioned automatic stoppage of the machine is caused but also the lamp 14 is caused to light, so that the operator at once perceives in which of the groups a thread has broken. If a means for 20 tripping an acoustic signal is provided further in the circuit, this signal is tripped at the same time and its sound alarms the operator. Owing to the comparatively small number of threads in each group, a breakage of a thread will be noticed at once, whereby 25 the object of the device is fulfilled. In place of connecting all threads of a group to one sole signal, a suitable subdivision of the group might of course be provided for.

In Figures 4 and 5 a signalling mechanism is illustrated in which the lamp signal described with reference to Figures 1 and 2 is replaced by the known electro-magnetic drop plate signal. During the operation of the machine the colored plate 16 is covered 30 in known manner by a drop plate 17 which is held in position by a pawl 18 under the action of an electro-magnet 22. Upon a thread breaking and thus the circuit being closed, the pawl 18 releases drop plate 17 35 which by gravity falls forward into the position illustrated in Figure 5 and leaves the signal plate 16 free to be seen by the operator.

In Figure 6 a special board is illustrated that may be applied e. g. on the top of the 40 creel or on the machine itself and serves to localize the electric light or color signals or electro-magnetic signals instead of distributing them at each individual thread guide bar of the creel. In this board a correspondingly numbered signal place is provided for each group of threads, each of these signals being connected to the contact plate 12 of the respective feeler carrier 1 to 9.

Figures 7 and 8 illustrate a purely mechanical embodiment of the invention. In this embodiment the thread guiding bar 1 has 45 swingingly mounted on it as in the embodiment described the feelers 10 which act also in the described manner. The contact plate 16 of the stop mechanism of the machine is

painted on its side turned toward the operator's stand with a bright color. A drop plate 19 covers the bright surface of plate 16 as long as no breakage of a thread occurs, and is held in covering position by a hook bar 20, the lower end of which is hingedly connected to a wire yoke 21. The latter is mounted for swinging motion on the shaft 11, and its middle portion is of such length as to engage all feelers 10 belonging to an individual group of the respective thread guide bar. Now, upon one of the feelers 10 falling down owing to the breakage of a thread, Figure 8, the feeler shifts the respective hook bar 20 upward, whereby the cover plate 19 is released and falls down so that the brightly colored plate 12 is free to be seen by the operator. Of course the described mechanism may be modified in any suitable manner allowing of the object aimed at to be obtained, provided always that one single indicating or signalling device is controlled by a plurality of feelers.

Claims:

1. In apparatus of the class described, a support, said support comprising a straight rod, sets of rigid conductive elements supported by said support and projecting laterally thereof, each of said sets comprising a pair of parallel elements, a series of guide hooks mounted on one of the elements of each set, each of said hooks being normally held out of contact with the other element of its associated set by the tension of a thread engaged thereby but being adapted to move into contact with said other element upon breakage of such thread, and a separate electric signalling circuit associated with each of said sets and completed upon such movement of any guide hook of a respective series.

2. Apparatus according to claim 1 according to which the support is electrically conductive and one of the elements of each set is in electrical connection therewith, the support forming a part of the circuit.

3. Apparatus according to claim 1 according to which one element of each set is in connection with the similar elements of the other sets through a common conductor.

4. Apparatus according to claim 1 according to which the support is electrically conductive and one of the elements of each set is in electrical connection therewith, the other elements being insulated from the support and connected by a common conductor, the frame and conductor forming parts of the circuit.

5. Apparatus according to claim 1 where- 125 in each set of conductive elements is mount- ed on a separate non-conductive bar fixed to the support.

6. Apparatus according to claim 1 where- 130 in each set of conductive elements is mount- ed on a separate non-conductive bar fixed to

the support, each of said bars having a thread-guiding edge parallel to its associated set of conductive elements.

7. In an apparatus of the type described, a support, a plurality of rigid insulating bars supported by said support and projecting laterally thereof, each of said bars carrying a conductive plate along one edge of said bar, a conductive rod arranged parallel to each of said bars and their associated plates, a plurality of conductive guide hooks pivoted on each of said rods, each of said hooks being normally held out of contact with its associated plate by the tension of a thread engaged thereby but being adapted to move into contact with said plate upon breakage of said thread, and a separate electric signaling circuit associated with each associated rod and plate and completed upon such movement of any guide hook of a respective group.

The foregoing specification signed at Cologne, Germany, this 21st day of February, 1929.
